UNITED STATES PATENT OFFICE.

CHESTER A. WATSON, OF BALLINGER, TEXAS.

CAN OPENER.

Application filed January 19, 1924. Serial No. 637,257.

To all whom it may concern:

Be it known that I, CHESTER A. WATSON, a citizen of the United States, residing at Ballinger, in the county of Runnels and State of Texas, have invented certain new and useful Improvements in Can Openers; and I do hereby declare the following to be a full, clear, and exact description of the invention, such as will enable others skilled in the art to which it appertains to make and use the same.

The invention relates to the class of implement designed for opening tin cans containing articles of food and for removing the metal caps closing bottles containing beverages and food relishes.

The invention provides an implement embodying an adjustable and removable cutter which is formed with a double cutting edge so as to operate effectively when moved in either direction.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a side view of a can opener embodying the invention, showing the same applied,

Figure 2 is a top plan view thereof,

Figure 3 is a sectional view on the line 3—3 of Figure 2, looking in the direction of the arrows,

Figure 4 is a sectional view on the line 4—4 of Figure 2, and

Figure 5 is a detail view of the device as seen from the bottom side.

Corresponding and like parts are referred to in the following description and designated in the several views of the drawings by like reference characters.

The implement comprises a handle 1, which, as shown, consists of a flat bar or elongated plate having a notch 2 in an end thereof to form a bottle cap remover and having a longitudinal slot 3 in which the lower end of a cutter 4 operates. A centering point 5 is provided at the slotted end to pierce the top 5a of a can and form a pivot

about which the implement is rotated in order to cause the cutter 4 to cut through the top in a manner well understood.

The cutter 4 consists of a blade, the active end of which is pointed and oppositely beveled to provide a double cutting edge, as shown most clearly in Figure 3. The cutting blade 4 is mounted in a holder 6 which consists of a flat tube, preferably formed by folding opposite edge portions of a metal strip. The closed side of the tube 6 is provided with a plurality of openings 7 which are adapted to receive the end 8 of a spring 9 mounted upon the holder, whereby to hold the cutter in the required adjusted position. One side of the tube is open, the same resulting from the space formed between the edge portions of the strip which do not come together. A guide is provided at the lower end of the holder to receive the handle 1 and consists of end portions of the tube bent in opposite directions so as to embrace opposite edge portions of the handle as indicated at 8, the extremities of the bent portions 8 being notched to receive opposite end portions of the cutter, as shown most clearly in Figure 5.

It will be readily understood that the blade 4 may be adjusted to project to a greater or less extent from the handle and by reason of the double cutting edge, the implement will operate effectively when rotated either to the right or to the left. It is also observed that the cutter may be readily removed from the holder to admit of sharpening or to be replaced as required.

What is claimed is:

1. A can opener comprising a handle bar adapted to swing with respect to the can, a holder rising from the bar and overlapping the same to prevent transverse displacement with respect to the bar, and a cutter disposed in the holder and extending through the bar serving to prevent accidental longitudinal displacement of the holder.

2. A can opener comprising a handle bar adapted to swing with respect to the can, a holder disposed transversely of the bar and having means integral therewith overlapping the bar and preventing displacement transversely therefrom, and a cutter carried by the holder and projecting through the bar.

3. A can opener comprising a handle bar adapted to swing with respect to the can, a holder disposed transversely of the bar and

having means integral therewith overlapping the bar and preventing displacement transversely therefrom, and a cutter carried by the holder and projecting through the 5 bar, and said means having a notch serving as a guide for the cutter.

4. A can opener comprising a handle bar adapted to swing relatively to the can, a holder disposed transversely of the bar, said 10 holder having integral portions in hooked relation to opposite sides of the bar, said bar

having a slot therethrough, the extremities of said portions being notched, a cutter carried by the holder extending through said slot and into said notches, and means to adjustably secure the cutter to the holder. 15

In testimony whereof I affix my signature in presence of two witnesses.

CHESTER A. WATSON.

Witnesses:

ESTES M. LYNN,
MRS. MACK TAYLOR.
